UNITED STATES PATENT OFFICE

2,612,946

FLAME SENSITIVE FUEL CUTOFF DEVICE

Clifton A. Cobb, University City, Mo., assignor to
 Missouri Automatic Control Corporation, St.
 Louis, Mo., a corporation of Missouri

Application October 20, 1947, Serial No. 780,920

8 Claims. (Cl. 158—137)

1

This invention relates to safety fuel cut-off devices of the type in which a fuel control member being normally biased to a cut-off position is moved manually to a fuel-on position, and in which mechanism actuated by flame sensitive means retains the control member in a fuel-on position while there is flame at the burner and automatically releases it upon loss of flame. It particularly relates to devices of this kind in which the fuel supply to both pilot and main burner is cut off upon loss of flame at the pilot burner and in which a safety feature is included to prevent the flow of any fuel to the main burner as the control is manually moved to a set position in order to relight the pilot.

It is an object of the invention to provide a generally new and improved flame sensitive fuel cut-off device which is quick acting and reliable in operation and which is not affected by high temperatures ambient to the burner flame.

It is a further object to provide a novel flame sensitive fuel cut-off device of the manual reset type in which the volume change due to vaporization and condensation of a high boiling point liquid, sensitive to the burner flame, is utilized to actuate mechanism for holding the device in a fuel-on position when there is flame at the burner, and for releasing it to return to a cut-off position upon loss of flame.

It is a further object to provide in a device of this character a pilot burner and a temperature sensitive bulb in which a continuous burner port supports an uninterrupted flame for heating the bulb and igniting the main burner and in which the bulb is formed and supported with respect to the flame port so as to be heated in its entirety.

It is a further object to provide an automatic trip and manual reset type fuel cut-off device for controlling the fuel supply to both pilot and main burners, which includes a compound valve structure and actuating mechanism therefor by which fuel may be admitted to the pilot burner exclusively, by manual operation, in the absence of flame at the burner.

It is a further object to provide a safety fuel cut-off device of this character having a compound valve and actuating mechanism therefor whereby the valve may be moved manually to a set position in which fuel is admitted to the pilot burner in the absence of flame and in which fuel is admitted to the main burner only after ignition of the pilot burner and the return of the manual setting mechanism.

Other objects and advantages will appear in

2

the following description when studied in connection with the accompanying drawings.

Referring to the drawings,

Fig. 1 is a cross sectional elevation of a fuel cut-off device constructed in accordance with the present invention. The remote temperature sensitive bulb is not, however, included in this view but is shown in enlarged detail in Fig. 6.

Fig. 2 is a partial view of the device shown in Fig. 1 showing the manual reset plunger slightly depressed and the main burner lock out latch in position to prevent opening of the main burner port as the plunger is further depressed to a set position.

Fig. 3 is a partial view of the device shown in Fig. 1, showing the manual reset plunger in a fully depressed position. In this position the pilot burner port is open, the main return spring is compressed, and the lock out latch member is in position to prevent opening of the main burner port by the counter spring.

Fig. 4 is a partial view showing the automatically actuated detent in set position wherein the upward return of the valve stem and therefore the closing of the valves by the main spring is prevented. The manual reset plunger is shown returned to its uppermost position and the lock out latch is moved to a position in which the sleeve member is released permitting the opening of the main burner port by counter spring pressure.

Fig. 5 is a sectional view in part of the lower valve body, taken on line 5—5 of Fig. 1, showing the outlet of the annular pilot port;

Fig. 6 is a cross sectional view of the temperature sensitive bulb shown attached to the upper portion of the pilot burner;

Fig. 7 is a top view of the pilot burner showing the burner port;

Fig. 8 is a partial view in section of the upper end of the pilot burner showing the burner port;

Fig. 9 is a front view of the upper part of the pilot burner showing the burner port;

Fig. 10 is a diagrammatic view of a fuel supply system for main and pilot gas burners embodying a safety fuel cut-off device constructed in accordance with the present invention.

In the diagrammatic view, Fig. 10, a pilot burner is generally indicated at 20 having a temperature sensitive bulb mounted thereon generally indicated at 21. A main burner (shown in part) is indicated at 22. Fuel is supplied to the main and pilot burners through a fuel line 23 which is connected to the inlet of a safety fuel cut-off valve generally indicated at 24. Lead-

ing from valve 24 is a fuel conduit 25 for supplying fuel to the pilot burner 20, and a fuel conduit 26 for supplying fuel to the main burner 22. Interposed in the conduit 26 is a valve 27 of any suitable type, which automatically controls the supply of fuel to the main burner for intermittent operation in accordance with requirements. Mounted on the cut-off valve 24 is a valve actuating mechanism generally indicated at 28, and there is a capillary tube 29 leading from the temperature sensitive bulb 21 to the mechanism.

Referring to Fig. 1, the valve 24 includes a body member 30 having an inlet 31 to which the fuel supply conduit 23 is connected, an outlet 32 to which the main burner fuel supply conduit 26 is connected, and a side outlet 33 (see detail Fig. 5) to which the pilot fuel supply conduit 25 is connected. The valve body is further provided with a separating wall 34 having a horizontal portion 35 in which is formed a central main burner port 36 and a concentric annular pilot port 37 having its outlet at 90° to the inlet 31 as indicated at 33. Surrounding the ports 36 and 37 and on the lower surface of wall 35 are formed concentric circular valve seats 38 and 39 on which seat an inner main burner valve element 40 and an outer pilot burner element 41 respectively.

The outer valve element 41 has a generally cup shaped upper portion 42 and a central downwardly extending hollow stem portion 43. The top surface or rim of the cup portion is faced with a suitable pliable material, such as leather, as indicated at 44. The inner valve element 40 is disc shaped and has a central perforation 45. The disc is provided with an upper facing of pliable material as indicated at 46. There is also an upper bearing plate 47 which together with the pliable facing is attached to the valve disc by rivets 48.

The valve body 30 is further provided with a lower threaded bore 49 which receives a threaded closure plug 50, and an upper concentric smooth bore 51 which receives and guides the valve stem assembly. The closure plug 50 has a central bore 52, which receives in sliding fit relationship the lower hollow stem portion of outer valve element 41, and an annular recess 53 which receives one end of a main valve return spring 54. The other end of spring 54 bears against the lower side of the valve element 41 urging it toward a closed position. Inner valve element 40 is urged toward a closed position by a spring 55 in the hollow stem portion 43 of the valve 41.

There is a valve stem 56, the lower end of which is reduced as indicated at 56a and which extends into the hollow stem portion 43 of valve 41 and bears against the lower closed end thereof. At its upper end the valve stem 56 is provided with a flange or head 57 and a downwardly extending longitudinal bore 58 which receives the lower reduced end of a manual reset plunger 59. The valve stem and its head 57 are joined by a tapered shoulder 57a. Surrounding valve stem 56 and having a sliding fit in the bore 51 is an upper sleeve member 60. There is also a lower sleeve member 61 having a sliding fit on the lower reduced portion 57 of the valve stem 56 and extending thru the perforation 45 in the inner valve member 40 and downward into the hollow stem portion 43 of valve 41 and bearing against the bottom thereof.

The upper end of the lower sleeve 61 has a

flange 62 which provides a surface for abutting the lower end of the larger upper sleeve. The under side of flange 62 also bears against the bearing plate 47 under certain conditions. The lower end of the larger upper sleeve 60 also has a flange 63. A counter spring 64 surrounding the upper sleeve 60 and bearing at its upper end against the valve body and at its lower end against the sleeve flange 63 overcomes the relatively light spring 55 under certain conditions and moves the inner valve member 40 to an open position.

A frame member 65 is mounted on top of valve body 30 and is attached thereto by screws 66. There is also a housing 67, for enclosing the valve actuating mechanism, which is attached to the upper part of the valve body by screws 68. A pliable sealing gasket 69 is provided between the housing and the valve body to insure a fluid tight seal. The housing 67 has a perforation at the top thru which projects a cup shaped sealing cap 70 movable with the manual reset plunger 59. The cap 70 is provided with a flange 71 and there is a pliable gasket 72 mounted on the flange to insure a fluid tight seal when the plunger is in its normal uppermost position. The upper end of plunger 59 is provided with a head 73; and a spring 74 which bears at one end against the frame member 65 and at its other end against the plunger head 73, normally holds the plunger and the sealing cap in their uppermost position, as indicated in Fig. 1.

Pivoted on the frame 65 at 75 is a lock out latch member 76 having an upper angularly formed follower portion 77 and a lower angularly formed latch portion 78. Latch member 76 is biased in a clockwise direction by a spring 79 and the upper follower end 77 continuously bears against the reset plunger 59. The reset plunger 59 has a reduced lower portion 80 and a tapered shoulder 81 is formed at the point of reduction. This tapered shoulder provides a cam surface which acts to rotate the lock out latch member 76 counterclockwise against spring 79 as the plunger is depressed. It will be noted that the lower end of the plunger 59 does not reach the bottom of the bore 58 in the valve stem when the plunger is in its uppermost position, as shown in Fig. 1, and that the plunger may be depressed somewhat initially before any downward movement is imparted to the valve stem or valve elements. This initial downward movement of the plunger is sufficient to place the follower end 77 of latch 76 on the large diameter portion of the plunger, whereby the latch is rotated counterclockwise, moving the latching end 78 into a groove 82 formed in the upper sleeve member 60 near its upper end.

Mounted on the side of the frame member 65 and attached thereto by screws 83 is an expandable element generally indicated at 84. The element consists of an inner flexible cup member 85 and an outer rigid cup member 86. The outer cup member is provided with a flange 87 through which the screws 83 pass for attachment. The side walls of the inner and outer cups are continuously joined by welding as indicated at 88 so as to form a high pressure fluid tight seal. Outer cup member 86 is provided with a perforated boss 89 into which is inserted one end of the capillary tube 29 and wherein it is attached by welding. The capillary tube is therefore in communication with the space between the bottoms of the cup members.

The other end of the capillary tube is attached

to the lower end of the temperature sensitive bulb 21, see Fig. 6. Bulb 21 has an upper elongated and curved chamber 91 and a concentric longitudinal bore 92, of smaller diameter than the chamber, extending from its lower end to the chamber. At the junction of the bore and the chamber, the shoulder is beveled, as indicated at 93. The capillary tube 29 is connected to the bulb by inserting into bore 92 to the point of its junction with the chamber and is attached therein by welding. It is important that the tube extend precisely to the upper end of the bore 92. The internal diameter of the capillary tube is very small and its relationship to the diameter of the bulb chamber 91 is in the order of 1 to 25. The bore 92 is of such diameter as to receive the capillary in push fit relationship.

The bulb 21 is attached near its lower end to the side of the pilot burner 20 by any suitable means, such as the strap 94. The pilot burner includes a burner head 95 consisting of a hollow tubular member having a closed upper end. There is a burner port formed near the upper end of the head, see Figs. 7, 8 and 9, which consists of a pair of horizontally spaced circular openings 96, a horizontal slot 97 joining the circular openings, and a vertical slot 98 which intersects the horizontal slot approximately midway between the circular openings, extends upwardly to the end of the burner head and then horizontally approximately half way across its closed upper end. The port is arranged symmetrically with respect to the vertical center line of the burner head and the bulb is mounted so that its vertical center line coincides with the center line of the burner head so that elongated flames supported by the circular openings 96 may be projected, without undue obstruction by the bulb, for ignition of the main burner. The bulb is also mounted so that a portion of the curved chamber 91 overlays the horizontal portion of port slot 98 whereby the bulb is impinged by flame along its entire length.

It will be seen that the bulb 21, the capillary tube 29 and the expansible element 84 form a sealed system. In the manufacture of the device, air is evacuated from this system, and with the bottom wall of the inner flexible cup 85 pressed against the bottom wall of the outer cup 86, so that there is substantially no space therebetween, the bulb and capillary are then filled with mercury. The expansible element 84 is so proportioned that its volume, when expanded to its safe working limit, is at least equal to the volume of chamber 91, so that it can receive substantially all of the mercury from the bulb. It is also desirable to proportion the element so that its fully expanded volume does not appreciably exceed the volume of chamber 91, in order that the full working expansion of the particular type expansible element used may be obtained.

Reference is made to my copending application titled "Temperature Responsive Control" Serial No. 773,646, filed September 12, 1947, in which I have shown and described a flame sensitive device utilizing the volume change due to vaporization of a small portion of a high boiling point liquid contained in a flame heated bulb, to displace the remainder of the liquid therein for the expansion of a connected expansible element. The flame responsive actuator embodied in the present invention employs this principle.

The frame 65 has a perforation 99 concentric with the expansible element in which is fitted a guide bushing 100. Slidably fitted in the guide bushing is a spring extended telescoping detent

assembly, generally indicated at 101. The detent assembly consists of a sleeve member 102, an inner slideable plunger member 103, an adjustable abutment element 104, a spring 105, and a retaining plug 106. The sleeve member is provided with a reduced bore at one end and the plunger element is reduced in diameter at one end to provide shoulders which limit the extension of the plunger. The plunger 103 is further provided with a longitudinal threaded bore which receives in threaded engagement the inner threaded end of the abutment element 104.

The abutment element is round at its outer end and is provided with flat surfaces as indicated at 104 adjacent to the outer end to facilitate adjustment by a wrench. The retaining plug 106 is pressed into the inner end of sleeve member 102. The sleeve member 102 is further provided with a flange 108 at its inner end. An element return spring 109, bearing at one end against the frame member 65 and at its other end against the sleeve flange, resiliently opposes the expansion of the element 84 and holds the detent constantly in contact with the movable wall of the inner cup member 85. The abutment member 104 is projected by the expansion of element 84 under certain conditions, as indicated in Fig. 4, to overlay the upper end of the valve stem and to hold the valve elements open. The flange 57 on the upper end of the valve stem provides a projecting surface which facilitates a definite tripping action and eliminates the possibility of the detent dragging on the stem at the moment of tripping.

Operation of the device

Fig. 1 shows the elements of the device in the position to which they automatically move upon loss of flame at the pilot burner. The detent 104 is in a retracted position, clear of the flange 57 on the upper end of the valve stem 55. The detent was moved to this position by the element return spring 109 as condensation of the vapor in bulb 21 progressed after loss of pilot flame. Valve elements 40 and 41 are both closed, and the valve stem 56, the sleeves 60 and 61 are moved to their uppermost position by the main valve return spring 54. In this position the counterspring 64 is compressed by the much stronger spring 54. The manually operated reset plunger 59 and the lock out latch 76 are in their normal positions, to which they are returned by springs 74 and 79 respectively.

In order to relight the pilot burner and admit fuel to the main burner, the manual reset plunger is fully depressed to the position shown in Fig. 3, wherein the valve stem and hollow stem portion 43 of the valve element 41 are bottomed in the bore 52 of the closure plug 50. This action moves the valve element 41 to an open position and places the upper end of the valve stem 56 slightly below the lower edge of the detent abutment element 104. As the reset plunger is moved downward however, the initial part of the movement, that is, that part of the movement which occurs before the lower end of the reset plunger bottoms in the bore 53 in the valve stem, causes the lock out latch to engage the groove 82 in the upper sleeve member 60. It will be seen that with the sleeve member 60 and consequently the stressed counterspring 64 thus retained, the main valve element 41 remains on its seat, by reason of the relatively light spring 55, as the valve stem continues downward to depress the main spring 54 and open the valve element 41. Fuel may now flow from the supply line 23 into the valve 24

thru the inlet 36, thru the annular port 37, thru the outlet 33, and thru conduit 25 to the pilot burner.

With the manual reset plunger held in a fully depressed position the pilot is ignited. The danger due to accumulation of a substantial volume of gas in the fire box flowing from the main burner, in event the automatic valve 27 is open due to requirement for heat, is obviated. After ignition the reset plunger is held in a depressed position for an interval in which the mercury in bulb 21 is sufficiently heated above the boiling point. As vaporizing occurs and progresses in bulb chamber 91 the vaporized portion will rise to the upper end of the chamber displacing the remainder of the liquid therein and expanding the expansible element 84.

As element 84 expands the detent assembly is moved outward and the abutment element 104 is moved into position over the edge of the flange 57 on the upper end of the valve stem 56, as shown in Fig. 4, wherein it prevents the upward return of the valve stem. When this occurs the device is in a set position and the manual reset plunger is released to return under pressure of spring 74 to its uppermost, normal position. As the reset plunger moves upward and the follower end 71 of the lock out latch 76 leaves the large upper diameter portion of the plunger, the latch is rotated clockwise by spring 75 and the latching end 78 moves out of the groove 82 releasing the sleeve member 60. Upon release of the sleeve member the counterspring 64, which was stressed by the stronger main spring 54, moves the inner valve element 40, controlling the main burner port, to its open position; and compresses the relatively light spring 55, as shown in Fig. 4.

Fuel may now flow through the port 36, through the outlet 32, and the conduit 26 to the main burner when requirements cause the valve 27 to open. The valves 40 and 41 will remain in this open and set position until the flame at the pilot burner fails or the fuel supply pressure drops below a predetermined point wherein it will not support a suitable flame to insure safe and dependable ignition of the main burner. When the flame at the pilot burner fails or diminishes below a predetermined point, condensation will take place in bulb chamber 91 and element return spring 109 will displace the liquid mercury from the element 84 and retract the detent. When the detent is withdrawn sufficiently to clear the edge of the valve stem head 57, both valves will be quickly closed, cutting off all fuel to the burners. The valve stem 56 and the sleeves 60 and 61 will also be returned to their uppermost positions and the counterspring 64 compressed.

Satisfactory operation of the device requires that the entire bulb chamber 91 be heated sufficiently by the pilot flame to displace all liquid therefrom so that the point of continued boiling will occur in the greatly restricted capillary tube. It will be noted that the flame port and bulb are so arranged to effect this. If boiling continues in the enlarged chamber 91 it will cause the expansible element to vibrate objectionably. It will also be noted that the single opening in the chamber 91 is at its lowest point. If the opening is not at the lowest point, mercury will continue to gravitate into the chamber and continue to boil therein causing a continuous surging of the expansible element.

The boiling point of the mercury and therefore the temperature at which the detent will be

actuated may be varied by varying the strength of the element return spring 109. It has been found desirable to spring load the expansible element to the extent that it requires a bulb temperature in excess of 800° F. to move the detent to a set position or to retain it in a set position. This temperature is well above any temperatures ambient to the pilot burner which are likely to be encountered in usual usage. If, however, it is found that the device can be operated at lower temperatures without danger of being affected by ambient temperatures, the spring load on the expansible element may be decreased and a more economical pilot flame may be used.

The time interval between ignition of the pilot burner and the movement of the detent to a set position, is, of course, not very critical, but it should not, as a matter of convenience, exceed one minute. This time interval will vary somewhat depending upon the temperature of the bulb at the time of ignition, the spring loading of the expansible element which determines the temperature which the bulb must attain, the design of the flame port and the fuel supply pressure, and the adjustment of the abutment element relative to the valve stem head.

The time interval between flame failure and the tripping of the device is more critical, however, to the extent at least, that the device does not trip upon a momentary flickering of the flame due to draft, or impurities in the fuel, and to the extent that a maximum period based on safety considerations must not be exceeded. The abutment element is adjusted therefore to satisfy these requirements. The spring loading of the element will also determine the time interval between flame failure and tripping. As the minimum temperature at which the device will set or trip is raised by increased spring pressure, the differential between this predetermined minimum and the maximum stabilized bulb temperature attainable with the flame will diminish and therefore, the time interval on cooling will diminish.

The abutment element has been arranged to telescope, and a tapered surface 57a on the under side of the head 57 has been provided to allow for the natural inclination of the operator to feel for the abutment element. If, after the pilot has been ignited he releases the manual reset plunger slightly, just sufficiently to move the head 57 above the abutment member at a time when it is just approaching the edge of the head, it would be impossible for him to again fully depress the plunger after a short interval without this provision.

The foregoing description is intended to be illustrative and not limiting and the exclusive use of all modifications within the scope of the appended claims is contemplated.

I claim:

1. In a manual reset valve in combination, a valve body having main and pilot burner fuel supply ports therein, first and second valves for controlling said main and pilot ports respectively, a main spring for holding said second valve closed, a secondary spring biased between said second and first valves for holding said first valve closed, a spring returned manual actuator for opening said second valve, a counter spring capable of opening said first valve against said secondary spring when said second valve is opened, means operated by said manual actuator as it is moved in a valve opening direction to restrain said counter spring, said restraining means be-

coming inoperative upon return of said manual actuator, and means operative under certain conditions to hold said second valve in an open position.

2. In a manual reset valve in combination, a valve body having main and pilot burner fuel supply ports therein, first and second valves for controlling said main and pilot ports respectively, a main spring biased between said valve body and said second valve for holding it closed, a secondary spring biased between said second and first valves for holding said first valve closed, a spring returned manual actuator for opening said second valve, a spring pressed member capable of opening said first valve against said secondary spring when said second valve is opened, a latch member moved to a position for restraining said spring pressed member as said manual actuator is moved in a valve opening direction, said latch member being moved to a releasing position as said actuator is returned, and means operative under certain conditions to hold said second valve in an open position.

3. In a manual reset fuel valve in combination, a valve body having main and pilot fuel supply ports therein, first and second valves for controlling said main and pilot ports respectively, a main spring biased between said valve body and said second valve for holding it closed, a secondary spring biased between said second and first valves for holding said first valve closed, a spring returned manual actuator for opening said second valve, said actuator having a lost motion connection with said second valve whereby said actuator may be moved an initial amount in a valve opening direction before said second valve is moved, a spring pressed member arranged to contact said first valve and move it to an open position against said secondary spring when said second valve is opened, said spring pressed member being restrained by said second valve when in a closed position, means rendered operative by the initial lost motion movement of said manual actuator in a valve opening direction to restrain said spring pressed member, said restraining means being rendered inoperative upon return of said actuator, and means operative under certain conditions to hold said second valve open.

4. In a device of the class described, a valve body having an inlet, a main outlet, a pilot outlet, a wall separating said inlet and main outlet, a main burner fuel supply port in said wall connecting said inlet and main outlet, an inner valve seat surrounding said port, an annular recess in said wall circumscribing said inner valve seat and having communication with said pilot outlet, an outer valve seat surrounding said annular recess, said valve seats and recess being on the inlet side of said wall, an inner disc valve adapted to engage said inner seat, an outer cup shaped valve adapted to engage at its rim with said outer valve seat, a relatively strong main spring biased between said valve body and said outer valve for holding it closed, a relatively light secondary spring biased between said outer and inner valves for holding said inner valve closed, manual means for opening said outer valve, said secondary spring being capable of retaining said inner valve in closed position when extended by the opening of said outer valve, and counter spring means of intermediate strength for opening said inner valve under certain conditions when said outer valve is open.

5. In a manual reset fuel valve in combina-

tion, a pilot burner, a valve body having main and pilot fuel supply ports therein, first and second valves for controlling said main and pilot ports respectively, a main spring for holding said second valve closed, a secondary spring for holding said first valve closed, a spring returned manual actuator for opening said second valve, said actuator having a lost motion connection with said second valve, whereby said actuator may be moved an initial amount in a valve opening direction before said second valve is moved, a spring pressed member arranged to contact said first valve and to move it to an open position against said secondary spring when said second valve is opened, said spring pressed member being restrained by said second valve when it is in a closed position, means rendered operative by the initial movement of said manual actuator in a valve opening direction to restrain said spring pressed member, said restraining means being rendered inoperative upon return of said actuator, and a flame sensitive device responsive to flame at said pilot burner for holding said second valve open when there is flame and releasing it upon loss of flame.

6. In a manual reset valve in combination, a valve body having an inlet, a main outlet, a pilot outlet, a wall separating said inlet and main outlet, a main burner fuel supply port in said wall connecting said inlet and main outlet, an inner valve seat surrounding said main port, an annular recess in said wall circumscribing said inner valve seat and having communication with said pilot outlet, an outer valve seat surrounding said annular recess, said valve seats and recess being on the inlet side of said wall, an inner reciprocating valve adapted to engage said inner valve seat, an outer reciprocating valve overlaying said inner valve and adapted to engage said outer valve seat, a relatively strong main spring for holding said outer valve closed, a relatively weak secondary spring for holding said main inner valve closed, a spring returned manual actuator for opening said outer valve, counterspring means of intermediate strength opposed by said main spring and being arranged to open said inner valve against said secondary spring when said outer valve is opened, means rendered operative upon initial valve opening movement of said manual actuator for restraining said counterspring means, said restraining means being rendered ineffective upon return of said manual actuator, and means operative under certain conditions for holding said outer valve open.

7. In a manual reset valve in combination, a valve body having main and pilot fuel supply ports therein, a posterior valve for controlling said main port, an anterior valve for jointly controlling both ports, a relatively strong main spring for holding said anterior valve closed, a relatively light secondary spring for holding said posterior valve closed, counterspring means of intermediate strength for opening said posterior valve against said secondary spring, said counter-spring being restrained by said anterior valve when in a closed position, a spring returned manual actuator for opening said anterior valve, means including a latch member moved to a position by initial valve opening movement of said actuator for withholding said counterspring means, said latch member being moved to a releasing position upon return of said actuator, and means operative under certain conditions for holding said anterior valve open.

8. In a device of the kind described, a valve body having an inlet, a main burner fuel supply outlet, and a pilot burner fuel supply outlet in the side walls thereof, a separating wall therein forming inlet and outlet chambers, said wall having a horizontal portion with its lower surface on the inlet side, a main port in said horizontal wall portion, an inner valve seat surrounding said port, an annular recess in said wall concentric with and circumscribing said inner valve seat and having communication with said pilot outlet, a concentric outer valve seat surrounding said recess, said valve seats and said recess being on the inlet side of said wall, an inner reciprocating disc valve adapted to engage said inner valve seat for controlling said main port, a cup-shaped outer valve adapted to engage at its rim with said outer valve seat for controlling both main and pilot ports, said outer valve having a concentric downwardly extending cylindrical portion with a closed lower end, a screw threaded bore concentric with said valve seats in the lower wall of said valve body opening into said inlet chamber and of sufficient diameter to permit the passing of said outer valve therethrough, a screw threaded closure plug fitted in said bore, said plug having a longitudinal bore for slidably receiving said cylindrical outer valve portion,

spring means for holding said outer valve closed, independent spring means for holding said inner valve closed, means for independently opening said outer valve, means operable under certain conditions for opening said inner valve when said outer valve is open, and means on said outer valve for rendering said last mentioned means inoperative when said outer valve is closed.
